ERNEST A. BARFIELD, OF MACON, GEORGIA

ENVELOPE LABEL HOLDER

Application filed May 14, 1929. Serial No. 362,988.

This invention relates to envelopes and the like and has special reference to an envelope label holder.

In many places, such as railroads and the like, large quantities of envelopes are used between different departments or different stations, the envelopes being destroyed after one usage because they have had the name and address of the addressee typed or written on them. Also, many railroads use envelopes for containing way-bills and the like which have a form on the front filled out for each shipment and thus such envelopes as this can only be used once as ordinarily constructed.

15 The principal and most important object of the present invention is to provide an improved envelope having transparent means on its face for holding a label which may have imprinted or written thereon the address of a 20 person as in correspondence or information as in the case of way-bill envelopes and the like.

A second important object of the invention is to provide an envelope of this character 25 having a transparent strip on its face for holding a label, the strip being provided with one or more windows for the insertion and removal of the label, said windows having their edges reinforced by turned under portions of the strip.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a view of the face of one envelope constructed in accordance with this invention and showing one form or arrangement of the transparent strip.

45 Figure 2 is a view similar to Figure 1 but showing only a portion of the envelope and strip in order to illustrate a modified form of window for admitting the label.

Figure 3 is a view similar to Figure 2 but 50 showing a second modification.

Figure 4 is a section on the line 4—4 of Figure 2, the thickness of the materials being exaggerated greatly.

Figure 5 is a view of one end of an envelope suitable for containing railroad way-bills and the like, the label used with this form carrying information blanks to be filled in, an example of which is shown in the drawing.

Figure 6 is a section on the line 6—6 of Figure 5, the thicknesses of the materials being exaggerated as in Figure 4.

In the present disclosure it is not deemed necessary to show the back of the envelope as any ordinary envelope may be used having a face 10 and in Figures 1 to 4 inclusive there is disclosed a strip of transparent material 11 which is secured at its edges to the envelope face 10 as indicated at 12. In Figure 1 it will be seen that at the left hand end of this strip there is an opening or window 13 which is formed by slitting the material of the strip 11 and turning the triangular tabs thus formed under the body of the material so that the edges of this opening 13 are reinforced and prevented from tearing when the label strip 14 bearing the address or the like is inserted. In Figure 1 it will be noted that this label strip 14 is short enough to pass entirely to the right of the opening 13 and in order to position the label so that it may be removed when desired a second opening 15 also reinforced by under turned portions is made at the right of the strip 11 so that the finger of the user may be inserted through this opening to frictionally engage the address label 14 and push it to the left for removal from the opening 13.

In Figure 2 there is provided an opening 16 for the insertion of the label 14, this opening being rectangular and the strip 14 being of such length that its left hand end will always remain in position to be grasped through the opening 16 when pushed to the right but the strip 14 may also be pushed so that its left hand end extends to the left of the opening 16. In Figure 3 there is provided an opening 17 of rectangular form reinforced by a single tab 18, the opening 17 being narrow laterally.

In Figures 5 and 6 there is shown a large envelope 19 such as is used to contain way-

bills and the like and on this large envelope is secured by mucilage 20 a transparent strip 21 open at one edge, the open edge being here indicated at 22 though the top edge may be 5 left open and the edge 22 closed if desired. Under this strip 21 is slid a card or label 23 bearing suitable information as indicated at 24. Also an opening 25 is provided similar to the opening 15 in Figure 1 and for the same 10 purpose.

Obviously in each of the cases here shown the envelope itself may be used repeatedly, it being merely necessary to remove the slip or label bearing the information and replace it 15 with another slip or label.

In some cases, where there is a great deal of correspondence between two certain persons the label used may have the address of one of these persons on one side and the address of the other person on the other side so that in the transmission of the envelope between the two it is merely necessary to place the label in position beneath the transparent strip with the proper side uppermost. In 20 using the type of the invention shown in Figure 5 it is obvious that the information on the slip or label may be of any desired character and while information has been here shown suitable for a railroad way-bill envelope it 25 is by no means my intention to confine the device to this use only as many other forms for other purposes may be used in this connection.

It is to be noted that in some instances it is preferred to have certain of the tabs which 30 reinforce the edges turned outwardly and pasted down as indicated at 26 in Figure 1, other tabs being turned under as at 27 and either left free or pasted down as may be desired. The object of turning some of these 35 tabs outwardly is to prevent catching of the tabs by the edge of the slip which is inserted or catching of this slip during its removal.

There has thus been provided a simple and efficient device of the kind described and for 40 the purpose specified.

It is obvious that minor changes may be made in the form and construction of the invention without departing from the material spirit thereof. It is not, therefore, desired to 45 confine the invention to the exact form herein shown and described, but it is desired to include all such as properly come within the scope claimed.

Having thus described the invention, what 50 is claimed as new, is:

1. The combination with an envelope; of a transparent strip secured at its edges to the face of the envelope to form a pocket, said strip having an opening therein provided with reinforced edges, and an information slip positioned in said pocket to lie between the envelope and transparent strip the width of said information slip being less than said opening whereby it may be moved therethrough for withdrawal and replacement.

2. The combination with an envelope; of a transparent strip secured at its edges to the face of the envelope to form a pocket, said strip having an opening therein provided with undeturned portions to form reinforced edges, and an information slip positioned in said pocket to lie between the envelope and transparent strip the width of said information slip being less than said opening whereby it may be moved therethrough for withdrawal and replacement.

3. The combination with an envelope; of a transparent strip secured at its edges to the face of the envelope to form a pocket, said strip having an opening therein provided with reinforced edges, and an information slip positioned in said pocket to lie between the envelope and transparent strip the width of said information slip being less than said opening whereby it may be moved therethrough for withdrawal and replacement, said strip having a second similar opening spaced from the first and having its greatest dimension less than the width of the information slip.

4. The combination with an envelope; of a transparent strip secured at its edges to the face of the envelope to form a pocket, said strip having an opening therein provided with undeturned portions to form reinforced edges, and an information slip positioned in said pocket to lie between the envelope and transparent strip the width of said information slip being less than said opening whereby it may be moved therethrough for withdrawal and replacement, said strip having a second similar opening spaced from the first and having its greatest dimension less than the width of the information slip.

5. The combination with an envelope; of a transparent strip secured at its edges to the face of the envelope to form a pocket, said strip having an opening therein provided with undeturned portions to form reinforced edges, said strip further having certain outward portions at the opening adhesively secured to the face of the strip, and an information slip positioned in said pocket to lie between the envelope and transparent strip the width of said information slip being less than said opening whereby it may be moved therethrough for withdrawal and replacement.

In testimony whereof I affix my signature.

ERNEST A. BARFIELD.
